PRESSING ELEMENT FOR PRESSING MACHINES

George W. Johnson, Cincinnati, Ohio, assignor to
The American Laundry Machinery Company,
Cincinnati, Ohio, a corporation of Ohio

Application October 17, 1933, Serial No. 693,958

7 Claims.

(Cl. 68—9)

This invention relates to a pressing element for pressing machines, and particularly one which is expandable by fluid pressure to apply heavy pressure after the press is closed.

5 An object of my invention is to provide an expandable pressing element which will equalize the pressure about the edges of the element.

Another object of the invention is to provide a pressing element of this type which does not 10 require a diaphragm of large area.

Another object of the invention is to provide an expandable element which will be economical in the use of fluid pressure.

Other objects and advantages will be apparent 15 from the following specification, together with the drawing, and the essential features of my invention are summarized in the claims.

In the drawing Figs. 1, 2 and 3 are elevations, generally in section, showing three modifications 20 of my invention as applied to a pressing bed; while Fig. 4 is a similar view of a pressing head embodying my invention.

While my improved pressing member is adapted 25 for use in many types of presses, I have illustrated it as applied to presses of the type used in garment or laundry work. In such presses a pair of coacting pressing members are provided with means for moving them apart to permit work to be arranged upon a pressing bed and thereafter 30 the members are moved into engagement and heavy pressure is applied to the work. I have not illustrated mechanism for so moving the pressing members as many such arrangements are well known in the art and form no part of the present 35 invention.

One or both of a pair of pressing members is usually provided with a yielding surface, such as 40 spring padding or the like, to enable the pressing bed to better accommodate itself to seams, buttons and other slight unevenness in the work. However, there is sometimes a greater variation in thickness between the ends or sides of a garment for which the yielding padding will not 45 compensate. Also, when the heavy pressure is applied through rigid arms it is difficult to distribute the pressure evenly over the surface of the pressing members. My improved element applies final pressure by means of fluid introduced 50 into an expandible member. The fluid permits the pressing member to accommodate itself to variations in work thickness and insures even distribution of pressure over the entire pressing surface.

55 Expansible pressing members involving large diaphragm or bag-like members are to be avoided

as they are expensive to construct and maintain.

My invention comprises in general a pressing element having two rigid portions spaced apart and movable toward and away from each other. Fluid pressure is introduced into the intermediate space to expand the element and sealing means is provided about the peripheries of the rigid portions to prevent leakage of the fluid medium.

Figs. 1 and 2 are similar in that each shows a 10 pressing bed having a base portion 10 supported on members 11, and a movable portion 12 on which is arranged a yielding padding comprising springs 13 and a fabric covering 14 which is held taut by carding wire strips 15.

In Fig. 1 the base portion has upstanding edge flanges 16, about the periphery of which are suitably secured vertically spaced yielding strips or cushions 17 and 18. These strips are preferably made of rubber having soft and yielding qualities. 20 A substantially horizontal flange 19 extends outwardly from the periphery of movable portion 12 in position to lie between cushions 17 and 18. Preferably the flange 19 is at all times in contact with cushions 17 and 18. A conduit 21 serves to 25 conduct fluid pressure from a source not shown to the space 22 between the base and movable portions of the pressing element.

Upon introduction of sufficient fluid pressure to space 22 the portion 12 will move upward to 30 apply ironing pressure between the pressing members. The cushioning and sealing strips 17 and 18 are made sufficiently deep and resilient to permit the vertical movement of flange 19 necessary to supply final pressure to the pressing members, while at all times sealing space 22 against 35 leakage.

The construction in Fig. 2 is similar to that of Fig. 1 except that the movable portion 12 has a 40 downwardly extending flange 23 about its periphery, which is horizontally spaced from an upstanding flange 24, which extends about the periphery of the base portion 10. An endless flexible sealing strip 25 is suitably secured between flanges 23 and 24 and effectively prevents any 45 loss of fluid, while permitting relative movement of the upper and lower portions of the pressing element toward and away from each other. This expansion of the pressing element is controlled by fluid pressure introduced by conduit 21 into 50 space 22.

The pressing members of Figs. 1 and 2 are wasteful of fluid pressure in that the entire 55 chamber 22 must be filled to create heavy pressure. Figs. 3 and 4 illustrate a modification in

which fluid pressure is conserved by being confined in a tubular member extending about the periphery of the movable portion. To expand the pressing member this tube only need be supplied with fluid pressure.

Fig. 3 shows a pressing bed having a base portion 26 supported on members 21. The base portion has upstanding edge flanges 28 shaped to support a flexible tube 29 which is connected by a conduit 30 with a suitable source of fluid pressure. A movable portion 31 is provided with a downwardly extending flange 32 which has a trough-shaped edge 33 to overlie and conform to the shape of tube 29. The portion 31 is provided with a grille 34 which supports a perforated plate 35 spaced from the bottom 36 to form a drainage chamber 37 which communicates with one or more suitably-located drains 38. Where the drain passes through the base portion 26 it is provided with a suitable bearing 39 to permit drain 38 to slide upwardly and downwardly as the pressing member expands and contracts. Surmounting the perforated plate 35 are springs 40 supporting a fabric cover 41. Moisture from the pressing operation thus passes through cover 41 and perforations of plate 35 into chamber 37 and drains away through conduit 38.

The drainage conduit 38 may serve the additional purpose of maintaining registration between portions 26 and 31 as the pressing element expands and contracts. To this end drain 38 may be made sufficiently strong and rigidly secured to portion 31.

The expansion of the pressing member of Fig. 3 is controlled by the admission of fluid to tube 29 and it will be apparent that pressure will be evenly distributed about the periphery of movable portion 31.

The modification of Fig. 4 is similar to Fig. 3 and represents my invention as applied to a pressing head. A chest 42 is suitably suspended from a head support 43 as by means of a stud 44. A spring 45, confined between the head 46 of stud 44 and the head support, serves to bias chest 42 in an upward direction. A rigid frame 47 may be retained in alignment with chest 42 by stud 44 or otherwise. Coacting trough members 48 and 49 are secured to the frame 47 and chest 42 respectively. Between the trough members is a tube 50 which confines fluid pressure supplied thereto through conduit 51 from a source not shown. If chest 42 is heated the tube 50 is protected from direct transmission of heat by heat insulators 52 between trough members 48 or 49 and the tube 50. A suitable coacting bed 53 is supported on member 54.

In operation, chest 42 and bed 53 are locked in engagement and heavy pressure is applied by admitting fluid pressure to tube 50 to expand it. This pressure will be distributed evenly about the periphery of chest 42. Upon deflation of the tube spring 45 will move chest 42 toward the head support 43 to separate the pressing members.

What I claim is:

1. A pressing element comprising, a fixed portion, a movable portion, said movable portion having a pressing bed and a drainage space beneath said bed, means for trapping fluid pressure between said portions to control the movement of said movable portion, said means being engageable with said portions and expansible in a direction normal thereto, and a drainage conduit passing through said fixed portion and communicating with said drainage space, said drainage conduit having a rigid connection with said movable portion and a bearing in said fixed portion, whereby said conduit serves to maintain substantial registration between said portions.

2. A pressing element comprising rigid portions arranged for relative movement toward and away from each other, a tubular member supporting one portion at its periphery only on the other portion, said tubular member being expansible in a direction normal to said portions.

3. A pressing element comprising a rigid support for a pressing surface, a base member, a tubular member between and engageable with said base member and support and positioned solely at the periphery of said support, said tubular member being expansible in a direction normal to the general plane of said pressing surface, and fluid means for expanding said tubular member.

4. A pressing element comprising, a pair of rigid frames separated by a tubular member, said member being expansible by fluid pressure in a direction substantially normal to the general plane of said frames, said member being positioned adjacent the periphery only of one of said frames, and yielding means urging said frames toward each other.

5. A pressing element comprising, a pair of heated rigid frames separated by a tubular member, said member being expansible by fluid pressure in a direction substantially normal to the general plane of said frames, heat insulating members between said tubular member and said frames, and fluid means for expanding said tubular member.

6. A pressing element comprising a rigid support for a pressing surface, a base member, hollow means between and engageable with said base member and support and positioned solely at the periphery of said support, said hollow means being expansible in a direction normal to the general plane of said pressing surface, and means for supplying motive fluid to said hollow means.

7. A pressing element comprising rigid portions arranged for relative movement toward and away from each other, one of said portions supporting a pressing surface, a tubular member supporting one portion on the other portion with the axis of the tubular member lying in a plane parallel to the pressing surface, and said tubular member being expansible in a direction normal to the general plane of said pressing surface.

GEORGE W. JOHNSON.
